The ornamental design for a wheel hub for shopping cart, as shown and described.

DESCRIPTION

FIG. 1 is a perspective view of a shopping cart wheel showing the hub design;

FIG. 2 is a side view of the wheel showing the hub design, the other side being identical;

FIG. 3 is an end view of the wheel; and,

FIG. 4 is a cross section view along section line 4—4 of FIG. 3, showing the wheel hub design.
